UNITED STATES PATENT OFFICE.

HARRY NEWMAN, OF BROOKLYN, NEW YORK.

WINDOW CLEANER.

Application filed August 16, 1922. Serial No. 582,325.

To all whom it may concern:

Be it known that I, HARRY NEWMAN, a citizen of Rumania, residing at Brooklyn, in the county of Kings and State of New York, have invented certain new and useful Improvements in Window Cleaners, of which the following is a clear and exact specification.

This invention relates to wiping or cleaning means for windows, and my improvements are particularly directed to a device of this character wherein cleaning elements are applicable, simultaneously, at both sides of a window pane, and wherein the cleaner carrying and actuating means are included in the sash construction.

My invention further comprehends the construction of the sash frame wholly of metal with hollow sides, top and bottom, the sides having slots for the reciprocatory passage of the cleaner carrying means; the top containing spring return means for the cleaners, and the bottom containing spring return means for closing the slots in the sides as and when the cleaners are moved upwardly.

Other features and advantages of my invention will hereinafter appear.

In the drawings:

Fig. 1 is a front elevation of a window sash embodying the features of my invention.

Fig. 2 is a top plan view thereof, partly in section.

Fig. 3 is a section on the line 3—3 of Fig. 1.

Fig. 4 is a horizontal section taken on the line 4—4 of Fig. 6.

Fig. 5 is a vertical section taken on the line 5—5 of Fig. 1.

Fig. 6 is a fragmentary view, partly in section, of one upper corner of the sash, and

Fig. 7 is a detail sectional view showing the cleaners and taken on the line 7—7 of Fig. 4.

In these views the window sash will be seen to comprise the side members 1 and 2, top 3 and bottom 4. These members or stiles are composed of sheet metallic material and each has substantially box-like structure, with its elements shaped and adapted to serve certain purposes. Thus, the top 3 is composed of the side elements 5, whose lower portions 6 are inturned, terminating in upturned flanges 7, that constitute a socket for the reception of the window pane 8; while

the upper ends of elements 5 are folded over inwardly, as at 9, to receive the upturned portions 10 of flanges 11 that depend from a closure, slide element 12, which thus 60 removably covers the box-like upper member 3.

The structure of this member 3 is reinforced by braces 13, secured as at 14 to the elements 5, and having upper flanges 15 to 65 support slide 12.

Similarly the side members 1 and 2 of the sash are each composed of side elements 16, which are actually the walls of a U-shaped formation, whose base is indicated at 17, 70 and constitutes the inner portion of the stile. This inner portion 17 has a central indentation or groove 18 to receive the pane 8, and at each side thereof it is provided with slots 19, for a purpose to be referred to hereinafter. An outer element 20 is suitably secured to the elements 16, to complete the box-like formation, reinforcement being provided by means of the braces 21.

Secured to the element 20, as at 22, is a 80 vertical guide 23 here shown to be angular in cross-section, the point of its connection with member 20 occurring at one of the corners of the guide. This guide extends up into the member 3, and is there provided 85 with the inward bridgement 24, which completes its hollow formation, the bridgement 24 being provided with a squared slot or aperture 25, to receive the squared end of a shaft 26, forming part of a spring roller 90 device which will be more particularly referred to hereinafter.

The guide 23, for the major portion of its length, is open at its inner side, to provide a vertical slot 27; and a carriage 28, which 95 fits freely within the guide, and is slidable therein, has an extension that protrudes through this slot, outside the guide. The carriage is shown as comprising an angled member, conforming in cross-section substantially to the shape of the guide, and its extension is in the form of two arms 29, which respectively pass out through the slots 19, in which they are capable of sliding movement, said arms 29 each having a terminal portion 30, capable of engagement 100 with the window cleaning members.

The window cleaning members are here shown as consisting each of a channel like frame 31, embracing a number of tongues 110 or plies of soft, flexible material, indicated at 32, having spacers 33, within the confines

of the frame, whereby the free ends of the tongues are held in normally separated relation to each other, and are thereby enabled to engage the pane with highly efficient wiping or cleansing effect.

The cleansing members extend across the pane, one at each side thereof, and are supported by tapes 34, 34, which are attached respectively to an arm 29 of each carriage 10 28, and are wound upon a spring return roller 35. This roller is hollow, with end caps 36, from which flanges 37 extend to prevent overrun of the tapes.

The caps 36 have central holes 38 to serve 15 as bearings for the shaft 26. A helical spring 39 within the roller stores energy, in the manner of a shade roller, as the roller is rotated by the extension of the tapes in moving the cleaners downwardly, to thus 20 automatically return the cleaners. A handle 40 may be secured to one of the cleaners for the downward cleansing stroke of both cleaners, which is performed manually.

For the purpose of covering the slots 19 25 when the cleaners are in their normal, upward position, to thus prevent the introduction of rain, dust, etc., into the hollow frame of the sash, I attach tapes 41, 41 respectively to each arm 30 of the carriages at 30 each side of the sash. These tapes 41 each extend through channels provided therefor, that consists of opposed, U-shaped folds 42, 42 in the elements 16 and 17, the tapes 35 thereby extending across, and closing slots 19; and spools 43, revolvably mounted in the lower frame member 4, and provided with spring return means 44, serve to automatici-

cally wind up the tapes 41 as the cleaner is drawn downwardly; but the spring 39, being more powerful than the combined 40 springs 44, has the normal tendency to unwind the tapes 41 with the return movement of the cleaners.

Variations within the spirit and scope of my invention are equally comprehended by 45 the foregoing disclosure.

I claim:

1. A window comprising a sash having hollow sides, top and bottom, a pane of glass engaged therein, cleaners disposed at 50 the respective sides of the pane, a carriage slideable within each sash side connected with the respective ends of the cleaners, spring return means for the carriages located in the sash top, the sash sides provided with 55 slots, at both sides of the pane, for the reciprocal movement of the cleaners, slot closure tapes engaged with the carriages, and spring return means for the tapes contained in the sash bottom.

2. A window composed of hollow metallic sash sides, top and bottom, having pane engaging means, and the sides having slots at each side of the pane, guides located in the sash sides, cleaners disposed at each side 65 of the pane, carriages slideable respectively within the guides and connecting, through the slots, with the cleaners, and lengthwise flexible slot closing means engaged with the carriages and operable therewith.

Signed at the borough of Manhattan, in the city, county and State of New York, this 15th day of August, 1922.

HARRY NEWMAN.
